UNITED STATES PATENT OFFICE

FREDERICK PREATOR AND DON R. SEELY, OF SALT LAKE CITY, UTAH, ASSIGNEES
TO THE UTAH RADIO PRODUCTS COMPANY, OF SALT LAKE CITY, UTAH, A CORPO-
RATION OF ILLINOIS

DYNAMIC LOUD-SPEAKER

Application filed March 2, 1929. Serial No. 343,942.

This invention relates to a dynamic loud speaker, and its principal objects are:

First. To prevent the breaking of the moving coil leads.

Second. To make savings in the cost of constructing and assembling.

Third. To add materially to the life of the delicate working parts of the speaker mechanism.

Fourth. To preserve the structural integrity of the vibratory system, no matter what the climatic conditions may be.

Under even date herewith, that is to say March 2, 1929, Serial No. 343,941, a separate 15 and co-pending application for patent entitled "Method of assembling vibratory systems" was filed. In the said separate application a method of assembling the vibratory system of the present invention is described 20 and claimed.

In loud speakers of the dynamic type, the moving or so-called "voice" coil is usually made of fiber or similar material rigidly held in a resilient spider, so that the coil may be 25 vibrated relatively to the pole pieces, whereby sound impulses are imparted to the conical diaphragm, the smaller end of which is attached to the coil mounting.

Usually, the spider is made in one piece 30 and is composed of a circular hub surrounded by an elongated rim, the hub and rim being spaced annularly apart from each other, but connected by substantially radial arms.

The extremities of the spider along the line 35 of its elongation, are remote from the arms, and are rigidly held in a stationary part of the speaker structure. This results in allowing the hub and the central portion of the rim to vibrate freely, but makes it necessary 40 for the leads by which electric current is conducted to the coils, to bridge a gap between the moving part of the spider and a stationary part of the speaker structure. Hence, the 45 leads are subjected to incessant movement when the coil is vibrating, thus causing the metal in the leads to crystallize and break after a comparatively short time. This, of course, stops the functioning of the entire 50 mechanism, and makes it advisable to send

the entire apparatus to the factory for repairs.

In our improved speaker, we make the spider of an electro-conductive material, preferably metal, and divided the spider into two parts in the plane thereof, preferably by removing a narrow zone of the metal on either side of its longitudinal center line, thus leaving a gap between two substantially symmetrical sections or semi-spiders. These semi-spiders we insulate, and make parts of the electrical circuit by means of which the coil is energized. Each semi-spider necessarily has a semi-hub and a semi-rim.

The circuit is formed by attaching the two leads from the coil to the two semi-hub portions, and the two input lines to the two semi-rim portions. By this means, current is conducted between the stationary parts of the semi-spiders and the movable parts thereof, through the spider structure itself, while the fine wires of the input lines terminate at the stationary parts of the semi-spiders and are not subjected to any objectionable motion whatsoever.

Essentially, the semi-spiders serve as supporting and spacing members for the moving coil and its mounting.

The features of this invention, for which the protection of Letters Patent of the United States is desired, are collectively grouped in the claims concluding this specification.

In the drawing, which illustrates merely one embodiment of this invention,

Fig. 1 represents a longitudinal center section taken on line 1—1, Fig. 2, part of the cone diaphragm being broken away;

Fig. 2, an elevation in the direction of arrow 2, Fig. 1, parts in the foreground to the left of line 2—2, Fig. 1, being omitted;

Fig. 3, a section on line 3—3, Fig. 2;

Fig. 4, an enlargement of the central portion of Fig. 1, showing most of the parts in elevation instead of in section;

Fig. 5, a detail of substantially the portion enclosed by the broken line 5 in Fig. 1, drawn to a scale considerably enlarged;

Fig. 6, a view in perspective showing a detail of the semi-hubs broken away from the semi-spiders; and

Fig. 7, a view similar to Fig. 6 showing a modification.

Referring to the drawing, the numeral 20 indicates the usual annular or outside pole piece on one face of which may be positioned the spacing ring 21 by means of which the voice or moving coil and its related parts are assured concentricity with the usual center pole piece or core (not shown). Upon the 10 opposite face of the annular pole piece may be secured the mounting ring 24, this being held by the screws 25 passing through the annular pole piece.

Carried by the mounting ring 24 and insulated therefrom by the fiber washers 26, 15 is a spider composed of the two preferably symmetrical but opposite sections, or substantially semi-spiders 27 and 27-1, these being separated from each other by cutting out a narrow strip from the original spider 20 stamping to define gaps 28 and 29.

Each spider section is composed of the semi-rim 30, the arm 31 and the semi-hub 32 which may carry the laterally projecting 25 semi-flange 34. The spider is mounted on the cylindrical paper sleeve 35 so that the semi-flanges 34 shall rest upon and be concentric with the sleeve 35. The spider may be rigidly secured to the sleeve 35 by means 30 of the wrapped layers of paper 36 and 37, Fig. 5. At 38 there may be a soft paper washer interposed between the edges of the layers 36 and 37 and semi-hubs 32, as a cushion. Spaced apart from the spider and 35 wound on the sleeve 35 is the coil 39, this being held in place by paper wrappings 40 and 41.

The ends of the spider are clamped in place on the mounting by means of the screws 40 42 bearing down on the fiber washers 43. The screws 42 are insulated from the spider, by the fiber sleeves 45.

Leads 46 and 47, from the coil, may be attached to the corresponding semi-hubs by 45 drops of solder 48. The spider semi-rims, at one of their stationary extremities, for instance 30-1, may have the lugs 49, to which are attached the respective input terminals 51 and 52 by means of drops of solder 53.

The usual cone diaphragm 56, having an 50 inwardly projecting hub 57, may be secured upon the paper wrappings 37, the outer rim of the cone (not shown) being mounted in the usual manner.

In order to afford greater security in attaching the spider semi-hubs to the sleeve 35, these may be made in the form shown in Fig. 7, where the semi-hubs 32-1 have, instead of 55 a continuous flange, what may be called a broken flange, this having portions cut out so as to have lugs 58 spaced apart from one another. The recesses retain a certain amount of glue or cement, which when dry, 60 forms interlocking masses cooperating with

the lugs 58, to hold the hubs in place upon the sleeve 35 and within the wrappings 37.

While a specific embodiment of this invention is herein shown and described, it is to be clearly understood that we reserve to ourselves the right to make such differences and variations in the construction and arrangement of the details of our device as may be suggested and demanded by the development and progress of the art or arts with which this invention is most closely identified. It is implied that such differences and variations however, shall come within the scope of the accompanying claims.

Having fully described our invention what we claim is:

1. A dynamic loud speaker comprising a pole piece, a spider composed of two electro-conductive sections spaced apart longitudinally and insulated from each other, and spaced apart and insulated from said pole piece, a voice coil mounting secured in said spider, a voice coil carried by said voice-coil mounting, one lead from the voice coil connected to one of said spider sections, the other lead of said voice coil attached to the other spider section, and input leads connected to the respective spider sections.

2. A dynamic loud speaker comprising a vibratory spider, said spider composed of two electro-conductive parts spaced apart from each other, a coil carried by said spider, one terminal of said coil attached to one of said spider parts, the other terminal of the said coil attached to the other part of said spider parts, and electric input leads attached to the two respective spider principal parts.

3. A vibratory system comprising a spider composed of semi-hubs spaced apart from each other and semi-rims spaced apart from each other and from said semi-hubs, a vibrating member supported in said semi-hubs, and a support for said semi-rims.

4. A vibratory system comprising two semi-spiders spaced apart from each other longitudinally, said semi-spiders having hub portions, flange portions projecting laterally from said hub-portions, a cylindrical vibratory member positioned in said hub portions, and wrappings of sheet material extending around said vibratory member and around said flange portions.

5. A dynamic loud speaker comprising a vibratory spider, said spider composed of two electro-conductive parts spaced apart from each other, a coil mounting and coil supported by said spider, one terminal of said coil attached to one of said spider parts, the other terminal of the said coil attached to the other of said spider parts, electrical input leads attached respectively to the said spider parts, a cushioning member adjacent said spider, and a diaphragm member having a hub portion positioned against said cushioning member.

6. A vibratory system comprising two semi-spiders spaced apart from each other longitudinally, said semi-spiders having hub portions, flange portions projecting laterally from said hub portions, a cylindrical vibratory member positioned in said hub portions, a plurality of layers of sheet material around said vibratory member and around said flange portions, a cushioning washer interposed between the edges of said layers and the said hub portions, and a diaphragm member seated around said layers and against said washer.

7. In a vibratory system, a spider composed of electro-conductive semi-spiders spaced apart from each other, each semi-spider comprising a semi-hub and a semi-rim spaced apart from said semi-hub.

8. In a vibratory system, a spider composed of electro-conductive semi-spiders spaced apart from each other, each semi-spider comprising a semi-hub, a semi-rim spaced apart from said semi-hub, and a substantially cylindrical semi-flange extending laterally from said semi-hub.

9. In a vibratory system, a spider composed of electro-conductive semi-spiders spaced apart from each other, each semi-spider comprising a semi-hub, a semi-rim spaced apart from said semi-hub, and a substantially cylindrical semi-flange extending laterally from said semi-hub, said semi-flange composed of a plurality of component sections spaced apart from one another.

35 10. In a vibratory system, a vibratory spider composed of a hub portion, a ring portion spaced apart therefrom, and a substantially cylindrical flange extending laterally from said hub, said flange consisting of a plurality of elemental sections spaced apart circumferentially from one another.

In testimony whereof we sign our names hereto.

FREDERICK PREATOR.

DON R. SEELY.
